UNITED STATES PATENT OFFICE

2,529,356

COIN-CONTROLLED MUSIC EXCHANGE

William Wolfe Shayne, Miami, Fla.

Application November 27, 1945, Serial No. 631,079

3 Claims. (Cl. 179—6.3)

1

This invention relates to coin controlled record apparatus.

An object of this invention is to provide an improved record playing system wherein a coin box and a loudspeaker may be disposed at one location and electrically connected to a central station, wherein the records selected at the coin box are played and then the sound is transmitted back to the loudspeaker.

Another object of this invention is to provide a central record playing station wherein a plurality of record playing members are located with each record playing member having a preselected record thereon and the record playing member is actuated through dropping of a coin at a remote point.

A further object of this invention is to provide an improved record transmitting system which operates on the principle of telephone dials so that the person dropping the coin in the coin box may dial a code character or number and when the dialing has been completed the selected record will be played and the sound transmitted back to the location of the coin box for audio transmission through a loudspeaker. With a system of this kind the servicing of the record playing members is simplified and the usual automatic record playing devices at present positioned in different locations will be eliminated.

To the foregoing objects, and others which may hereinafter more fully appear, the invention consists of the novel construction, combination and arrangement of parts, as will be more specifically referred to and illustrated in the accompanying drawings, but it is to be understood that changes, variations and modifications may be resorted to which fall within the scope of the invention as claimed.

In the drawings:

Figure 1 is a diametrical view of a record playing system constructed according to an embodiment of this invention.

Figure 2 is a fragmentary front elevation of the coin box.

Figure 3 is a schematic view of the electric circuits embodied in this invention.

Figure 4 is a schematic view of the pre-amplifier, and

Figure 5 is a schematic view of the power supply for the selector.

Referring to the drawing, the numeral 10 designates generally a relay exchange of the type at present in use in automatic or dial telephone systems. The relay means 10 is connected by means of a conductor 11 to a remotely

2

disposed coin controlled selector box 12. The selector box 12 includes a dial 13 of the type at present in use on dial telephones. The selector member 12 is also connected by means of a conductor 14 to a ground or return conductor, so as to provide the complete circuit to the relay means 10. The selector member 12 has positioned on the outer face thereof the titles 15 of records which it is desired to have played and each title 15 has associated therewith code characters or numerals 16 which are similar to the characters and numerals at present appearing on dial telephones and there may be any desired number of these characters or numerals.

15 A loudspeaker 17 is positioned at the same location as the selector 12 and is electrically connected by means of a wire 18 to the relay means 10 and by means of a wire 19 to the ground or return. The relay means 10, which is positioned 20 at the central location or station, has connected thereto a plurality of record playing members, generally designated as 20. Each record playing member 20 includes a motor 21 having a turn table 22 operated thereby and on which a record 25 is adapted to be positioned. A tone or needle carrying arm 23 is adapted to engage the record on the table 22 and is connected by means of conductors 24 and 25 to the relay means 10 and to the loudspeaker 17. The relay means 10 is 30 of such construction that when the dial 13 is turned in accordance with the code characters 16 a circuit will be completed to a preselected motor 21 and to the tone arm or transmitter 23, so that the sound picked up by the tone arm 23 35 will be transmitted back to the location through the conductors 18 and 19 to the loudspeaker.

As shown in Figure 3 the central location is provided with a plurality of record playing devices 20 which are connected to the selector 13. 40 The record playing devices 20 each includes a motor 21 connected at one side, as at 26, to a source of current supply and connected at the other side by means of a conductor 27 to a relay operated switch 28, which is normally biased to 45 an open or circuit breaking position. A relay 29 actuates the switch 28 for moving the latter to closed position having one side 30 connected to the ground and the other side 31 connected to one of a series of contacts 32 arranged in a circle 50 which are wiped by a wiper 33 carried by an arm 34. The arm 34 is fixed to and insulated from a shaft 35. There will be a relay 29 and a switch 28 for each record playing motor and each relay will be connected to one of the contacts 32. The 55 tone arm 23 which engages the record on the

table 22 when the latter is elevated by conventional elevating means and tone arm 23 is connected by means of a pair of conductors 24 and 25 to a pre-amplifier, generally designated as 36. The pre-amplifier 36 embodies a pair of amplifying tubes 37 and 38, shown in Figure 4, which are connected to a power transformer 39 of conventional construction having a suitable plug connector as shown.

One side 40 of the output side of the pre-amplifier 36 is connected by means of a conductor 40 to one end of a primary transformer 41. The other end of the primary 41 is connected by conductor 42 to a wiper carrying arm 43 also mounted on and insulated from the shaft 35. The arm 43 carries a wiper 44 adapted to wipe over a series of circumferentially spaced contacts 46 and the contacts 46 are each connected by a wire 47 to the other side of the output of the pre-amplifier 36. The stepper arm 34 is connected by means of a conductor 48 to a power supply unit, generally designated as 49, shown in detail in Figure 5. The stepper arm 34 is also connected by means of a conductor 50 to one side of a relay operated switch 51 normally biased to an open position.

The switch 51 is moved to a circuit closing position when the relay 52 is energized. The relay 52 is connected at one end by means of a conductor 53 to a common ground or return and is connected at the other end to a conductor 54. A plurality of circumferentially spaced contacts 55 are connected together by connecting members 56 which are connected by a conductor 84 to conductor 48. A wiper carrying arm 57 is also mounted on the shaft 35 being insulated therefrom and carries a wiper 58 adapted to wipe over the connected contacts 55. The arm 57 is connected by a conductor 59 to a contact 60 forming part of a double switch actuated by means of a relay 61 connected at one side to the wire 59 and at the other side to the ground. A second contact 62 confronts the contact 60 being normally biased to a circuit breaking position and is connected by means of a conductor 63 to one side or contact 64 of a table actuated switch, generally designated as 65. The contact 64 includes an arm 68 disposed in the path of the vertical movement of the table 22 so that when the latter moves downwardly to reset position, contacts 64 and 66 will be closed.

A second switch 70 is actuated by the relay 61 and includes one contact 69 connected to the conductor 67 which connects to a contact 66 confronting the contact 64. The switch 70 includes a second contact 71 which is connected by a conductor 72 to one side or contact 73 of a solenoid operated switch 74. The switch 74 includes a second contact 75 normally biased to a circuit breaking position and moved to a circuit closing position when the coil 76 is deenergized and the core 77 moves downwardly to its normal position. The coil 76 is connected by a conductor 78 to one side or contact 79 of the relay operated switch 51 and the other side 80 of the switch 51, which is normally biased to a circuit breaking position, is connected by the conductor 50 to the conductor 48 and power supply unit 49 as well as arm 34. When the solenoid coil 76 is energized through closing of the circuit to the relay 52 of relay means 10 by insertion of a proper coin in the coin slot of the coin controlled selector box 12 and operation of the dial or impulse transmitter 13 the core 77 is moved upwardly thereby rocking a stepper arm or lever

81 carrying a pawl 82 which engages a ratchet 83. The ratchet 83 is mounted on the shaft 35 so that upon movement of the lever 81 the shaft 35 will be rotated step by step according to the number selected and dialed on the dial 13. The conductor 54 is connected to the secondary 85 of the transformer 86 and a condenser 87 is interposed in the conductor 54 adjacent one end of the secondary 85. The other end of the secondary 85 is connected by the conductor 14 to the ground and a condenser 88 is interposed in the conductor 14. The conductor 11 is connected to the conductor 54 and is also connected to a resilient contact 89 positioned in the path of a rotating pin 90 carried by the dial 91 of the dial structure 13. The pin 90, when the dial 91 is at rest, urges the contact 89 into engagement with a second contact 92 which is connected by means of a conductor 93 to the input of the amplifier at the receiving station (not shown) one side of the main amplifier (not shown). A third contact 94 is correlated with the contact 89 being normally disengaged therefrom when pin 90 is at rest but adapted to engage contact 89 when the latter is released by the pin 90 and permitted to resiliently flex against contact 94 so as to close a circuit through conductor 95.

The switch 96 includes a contact 97 connected to the conductor 95 and also includes a resilient contact 98 connected to a source of power in the amplifier and normally disengaged from the contact 97 and adapted to be intermittently moved into engagement with contact 97 by rocking of a rockable crank member 99. The crank member 99 is intermittently rocked a predetermined number of times by engagement with pins 100 carried by the dial 91 as the latter is rotated in a counter-clockwise direction as viewed in Figure 3 depending upon the dial number selected. The intermittent closing of switch 96 will result in the flow of electrical impulses from the contact 98, connected to a source of electrical power, to the contact 97, through the conductor 95 to the closed contacts 94 and 89, and then through the conductor 11 and the conductor 54 to the relay 52. These impulses will intermittently close the switch 51, and a pulsing current will then flow from the power supply for the selector 49, through the connector plug 111, the conductor 48, the conductor 50, the closed contacts 80 and 79, the conductor 78 to the solenoid coil 76 and to ground. The pulsing current from the power supply 49 will intermittently energize the coil 76 and will reciprocate the core 77 and rock the lever 81 connected to the latter. The pawl 82 carried by the lever 81 will rotate the ratchet wheel 83 and the shaft 35 to which the wheel is attached. The degree of rotation of the shaft 35 will depend upon the dial number selected. The arms 34, 43 and 57 will rotate with the shaft 35 to engage the movable contacts 33, 44, and 58 with the fixed contacts 32, 46, and 55 respectively. Current will then flow from the power supply through the conductor 48, the arm 34, the contacts 33 and 32, to the conductor 31 for energizing the relay 29 of the selected phonograph device. Energization of the relay 29 will effect the closing of the switch 28 and operation of the turntable motor 21.

The record on the turntable 22 will be engaged by the stylus 23 and the pickup 24 will produce an electrical current which will be amplified by the pre-amplifier 36 and will then flow in the circuit defined by the conductor 47, the contacts 46 and 44, the arm 43, the conductor 42, the wind-

ing 41 of the transformer, and the conductor 40. The flow of current in the primary winding 41, will induce a pulsating current in the secondary winding 85, which current will flow through the conductor 11, the contact 89, the contact 92, to the conductor 93 and hence to the amplifier at the receiving station.

When the record has been completely played, the turntable 22 will move to reset position and will depress the contact 64 against contact 66. Current will then flow from the power supply 49, through the conductor 84, the connectors 56 and the contacts 55 and 58 into the arm 57 and through the conductor 59 to the closed contacts 60 and 62. From the latter current will flow through the conductor 63, the closed contacts 64 and 66, the conductor 67, and the closed contacts 69 and 71 to the conductor 72 which connects to the contact 73 of the normally closed switch 74. From the contact 75 of the switch 74, the current will flow through the coil 76 to ground, thereby energizing the coil and moving the core 77 and the pawl 82. Such movement of the core 77 will also effect the opening of switch 74 so that the pawl 82 will be reciprocated, thus rotating the shaft 35. This step-by-step rotation of the shaft will continue until the arm 57 is positioned as shown in Figure 3, that is, with the contact 58 disengaged from the contacts 55 in which position the coil 61 is de-energized and the contacts 69 and 62 are separated from the contacts 71 and 60 respectively. The selector will then be in position for the selection of a turntable as described above by dialing at 13.

The power supply for the selector includes, as shown in Figure 5, a rectifier 101 of conventional construction connected to the secondary 102 of a power transformer 103. The output of the rectifier 101 is connected by conductors 104 and 105 to an outlet connector 106. A fuse 107 is interposed in one of the conductors between the rectifier 101 and the secondary 102 and a fuse 108 is interposed in one of the power lines leading to the primary 109 of the transformer 103 and having a suitable plug connector as shown. The conductor 104 is grounded, as indicated at 110, and a connector 111 which engages the connector 106 has one terminal thereof grounded by a conductor 112 and the others connected to conductors 84 and 48. Contact 98 of switch 96 is connected to the main amplifier (not shown) on one side of the circuit of the amplifier, and wire 93 is also connected to the main amplifier. The connection of the contact 98 with the main amplifier is for the purpose of obtaining a relatively low voltage current to relay 52, whereby when the dialing operation has been completed and pin 90 is at rest, the switch formed by the contacts 89 and 92 will be closed to wire 93 to supply a current of higher voltage.

What I claim is:

1. A coin controlled record playing system comprising a central station, a plurality of record playing means at said central station, remotely disposed play translating devices electrically connected to said playing means, a selector means for each of said translating devices, said selector means having a rotary switch means formed with radially disposed sequentially spaced play positions with electrical connections extending therefrom to each of said playing means and an open circuit no play position placed in radial sequence relative thereto, said rotary switch having means whereby it is rotatable in one direction, a rotating means, connecting means connected to said

switch whereby said switch is rotated in said one direction, said rotating means having a ratchet member, a solenoid, a reciprocative pawl operative by said solenoid and engageable with said member whereby rotation is imparted to the switch on reciprocation of the pawl, said solenoid means reciprocating said pawl on pulsed current energization thereof, an impulse generating means, means whereby said impulse generating means is associated with said translating means and connected to said solenoid for imparting electrical impulses thereto representative of a record selected for playing, means whereby said solenoid is responsive to said electrical impulses to reciprocate said pawl and rotate the switch through said positions in sequence to the position of selection, an electrical means in circuit with the playing means having a normally open contact connected to said selector solenoid, switch means in said circuit connected with the playing means and operative to alternately close and open said circuit for intermittent energization of the selector solenoid to rotate said rotary switch to said open position ready for repeat selective play operation.

2. A coin controlled record playing system comprising a central station, a plurality of record playing means at said station, remotely disposed play translating devices, an electrical impulse sending means operatively connected with each of said translating devices, a rotary selector switch for each of said translating devices having electrical connecting means extending between each playing means and the translating device, said selector switch having means whereby it is rotatable in one direction, operating means for rotating said selector switch in response to impulses sent by said impulse sending means, a second impulse sending means connected to the playing means and operative on completion of play, said second impulse means being connected to said operating means to rotate the selector switch to a reset position, and separate switch means in circuit with said second impulse means for opening said last mentioned circuit on rotation of said selector switch to said reset position.

3. A coin controlled record playing system comprising a central station, a plurality of record reproducing devices at said central station, a remotely disposed receiving station having means for originating a record selection signal, a selector switch for each receiving station, said switch having a plurality of sequentially spaced play positions and a reset position, with each of said play positions being connected to an individual reproducing device, and arm means rotatable in one direction through said positions for closing the circuit between said reproducing device and said receiving station as selected, said arm being adapted for further rotation after completion of play for movement to said reset position, a rotating means, said rotating means being operatively connected to said switch and responsive to said signal for moving said arm means to a selective play connecting position, an electrical means in circuit with said rotating means and operative by said playing means at the end of play for energization of the rotating means to reestablish rotation of the selector arm and move it from a play position to a reset position, and a separate switch means in said last mentioned circuit operative to disconnect the circuit on rotation of said arm to the reset position.
